OF DELAWARE

MEASURED SERVICE TELEPHONE SYSTEM

Application filed August 23, 1930. Serial No. 477,338.

The present invention relates to measured service telephone systems in general, but is concerned more particularly with measured service telephone systems in which calls are extended by automatic switches; and the principal object, briefly stated, is the provision of new and improved circuit arrangements for such systems in which the subscribers are given a choice of several classes of metered service.

An individual subscriber may choose any one of the following three different classes of metered service; (A) the subscriber pays a message rate for each call within the main (local) zone and on a zone and time basis to the north and south zones; (B) the subscriber pays a flat rate which will entitle him to free calls within the main or local zone and a fixed rate for each period of five minutes or fraction thereof on all calls to the north or south zones; (C) the subscriber pays a monthly rate which entitles him to free calls within the main or local zone as well as to either the north or south zones and for calls into zones not covered by the free call arrangement, he pays on the basis of a fixed rate for each period of five minutes or fraction thereof.

Another object of the invention is to provide a measured service system for party line subscribers in which the party line subscribers receive class (B) metered service; that is, the subscribers pay a flat rate which will entitle them to free calls within the main or local zone and a fixed rate on a time basis on all calls to the north and south zones.

A further object of the invention is to provide improved circuits and equipment which is common to a large number of party and individual subscribers' lines. Both party line and individual line subscribers may be assigned to the same group of lines and all the subscribers have the same line equipment at the exchange regardless of the class of metered service furnished to each line.

One of the features of the present invention relates to the means whereby if a calling subscriber dials before he receives dial tone, and therefore before a common meter

control equipment is selected, the subscriber is given a busy tone.

Other objects, not specifically mentioned here will best be understood by reading the detailed description and claims which follow:

The drawings comprising Figs. 1-4, inclusive, arranged with Fig. 2 to the right of Fig. 1 and Fig. 3 below Fig. 2 show sufficient circuit details to enable the invention to be described and understood.

Referring now to Fig. 1 in more detail, there is shown at the left-hand side of the drawings two subscribers' lines, the upper line being a party line including two substation circuits S' and S and the lower line being an individual line with the substation circuit S². The substation circuits S and S² are identical, while in the substation S' the shunt springs SS' of the calling device have been modified somewhat and will be more fully described later. Both lines terminate in similar line equipment comprising the usual line and cut-off relays, connector and finder banks. A meter relay is associated with each line for controlling the operation of the subscriber's meters, such as 28, 29, 28' and 31. The meter 28 is individual to subscriber S and the meter 29 is individual to subscriber S'. The meters 31 and 28' are individual to subscriber S². These and other similar subscribers' lines are accessible to a group of line finders, one of which is schematically shown to the right of the line and cut-off relays.

This line finder is somewhat similar to the line finder disclosed in Patent No. 1,851,132, issued to N. H. Saunders.

In Fig. 2 is shown the selector repeater SR which is permanently connected to the line finder shown in Fig. 1. This selector repeater is somewhat similar to the selector repeater shown in Patent No. 1,332,217, issued March 2, 1920, to Emil Jacobsen, but the circuits have been modified somewhat in accordance with the present invention. Associated with each selector repeater is a class minor switch CMS having wipers 280 and 281 which are advanced step-by-step by the rotary magnet 284 and returned to normal position by release

magnet 283. A time switch TS, similar in construction to the control minor switch CMS, is also associated with each selector repeater. At the lower part of Fig. 2 there is shown the common conductors 43 to 47, inclusive, which extend from the lower banks of the class minor switches to the contacts of the meter relays. This group of conductors as well as conductors 301 to 306, inclusive, are common to this particular group of finder-selector-repeater links.

In the upper-right-hand corner of Fig. 3 there is shown the classification switch finder CSF which is also individual to the selector repeater SR. The finder CSF is mechanically similar to the well known rotary line-switch which advances its wipers step-by-step and which wipers have no normal position. At MIR there is shown one of a group of meter impulse relays. This group of relays is individual to this group of finder-selector-repeater links and are controlled by a constantly rotating impulse distributor ID which is common to all the groups of finder-selector-repeater links in the exchange.

The wipers of the finder CSF have access to a group of classification switches one of which is shown at CS. The classification switch CS is of the well known Strowger vertical and rotary type of switch. Associated with each classification switch is a rotary control switch, such as RCS which is similar in construction to the well known rotary line-switch. Dependent upon the class of metering service to be provided for each particular exchange in the telephone area, certain contacts in the bank of the classification switch CS are jumpered and connected to certain bank contacts of the rotary control switch RCS.

Fig. 4 shows a detailed view of the shunt spring combination of the calling device of substation S'.

General operation

When the calling subscriber initiates a call, the subscriber's line relay is energized to initiate the operation of the finder which hunts for and finds the calling line. As soon as the finder finds the calling line the classification finder CSF associated with the finder-selector-repeater link hunts for an idle classification switch and when this is found the calling subscriber is given the well known dial tone.

In case the subscriber should dial before the receipt of dial tone, the selector repeater is operated to the level dialled and is automatically rotated to its eleventh position from where the busy tone is given to the subscriber.

Assuming that the subscriber waits for dial tone and on receipt thereof dials the first digit of the desired number to step the selector repeater to the required level from which point the selector will rotate and select an idle sec-

ond selector. At the same time that the impulses for operating the selector repeater were sent, pulses were also being delivered by way of the classification finder CSF to operate the selected classification switch CS.

After the first digit the selector-repeater SR rotates its wipers to select an idle second selector and the rotary control switch RCS advances one step to transfer the impulsive circuit from the vertical magnet to the rotary magnet of classification switch CS.

Responsive to the calling subscriber dialing the second digit of the desired number the selector repeater repeats these impulses to the second selector and to the rotary magnet of the classification switch. The classification switch rotates its wiper in accordance with this digit and grounds a particular contact in its bank. After the second digit the rotary control switch RCS advances to third position from where it is automatically operated step-by-step by relay 385 which is now connected to a common pulsing lead. The class minor switch CMS is operated by relay 385 in unison with the rotary control switch.

The step-by-step operation of the class minor switch and the rotary control switch continues until the wiper 364 of the rotary control switch connects with a contact in its bank which is connected to the grounded contact in classification switch bank. When this contact is reached, both the class minor switch CMS and the rotary control switch RCS stop. The class minor switch CMS is held in this position to control the metering when the called party answers, while the classification switch CS and rotary control switch RCS return to normal for use in other calls.

Depending on the class of metering to be produced when any particular office or digits are dialled, the classification switch bank is jumpered to the bank contacts accessible to wiper 364 of the rotary control switch RCS.

When the called subscriber answers a relay operation takes place which operates the calling subscriber's meter relay and an impulse is sent over one of common metering leads to operate the subscriber's meter in accordance with the setting of the class minor switch. In this case since the called subscriber is in the same zone and the calling subscriber pays for every such call on a metered basis the class minor switch is in position one. A single impulse is then sent over lead 43 to operate the calling subscriber's meter at the time the meter relay is in operated position. The calling subscriber's meter is therefore operated once for this type of call.

At this time it should be pointed out that for the different classes of metered service provided there will be another meter connected to this particular subscriber's meter relay. This meter has two windings and will be connected to leads 49 and 51 in order to

charge for calls into the north and south zones.

Assuming that the calling subscriber dialled a number in the north zone instead of the local zone the operations are the same as just described with the exception that the classification switch is operated to ground a contact which is connected to another bank contact in the rotary control switch RCS. The rotary control switch and the class minor switch are therefore again stepped in unison and the class minor switch CMS is stopped in second position when the rotary control switch RCS finds the grounded contact.

When the called party answers on this call the relay operation again takes place in response to the timed pulse arrangement to operate the meter relay and the subscriber's meter, this time over lead 44 since the call was to the north zone. Since the class minor switch is now in position two the time switch TS is operated step-by-step for the duration of the call to first apply a warning tone to the calling line and to operate the meter another step in case the calling subscriber continues to maintain the connection. The meter is therefore operated once when the called party answers and once for every predetermined time interval thereafter depending on the length of the conversation. In case the call was to the south zone the classification switch CS, the rotary control switch RCS and the class minor switch CMS would be stepped to corresponding positions and when the called subscriber answers the relay operation and metering would take place similar to the north zone, this time, however, the metering would be over lead 46.

From the above brief description it can readily be seen that the class of metered service as outlined under the classes B and C can easily be given in the case of class B by omitting the meter connected to leads 33 or 48 and connecting a double wound meter to leads 34 and 36 or leads 49 and 51. In the case of service under class C the meter on lead 33 is omitted and a meter is connected to either lead 34 or 36 as the case may be.

As previously stated, metered party line service is furnished with this equipment but in this case the subscriber can only have the type of service underlined under class B, that is, he pays a monthly rate sufficient to insure free calls in the main or local zone and pays for calls on the time basis to the north and south zones.

In the case of calls from the first party on the party line, the meter operation is identical with that outlined for single line subscribers having class B service. The second party's telephone is equipped with a dial or calling device which delivers a ground pulse to the line prior to the sending of each digit as well as after the digit. The pulses sent out after each digit have no par-

ticular significance, because only the first ground pulse is utilized to produce the desired effect. After the second party subscriber has reached the first selector repeater and obtained the dial tone, he will start dialling in the usual manner. As soon as he turns his dial, however, a momentary ground pulse will be placed on the line and this will cause differential relay 203 to operate on account of one of its windings becoming shunted. The operation of relay 203 will cause the resistance 230 in the holding lead to the classification switch to be shunted out and this occurrence will cause marginal relay 384 in the classification switch to operate and lock itself to ground on the guard lead 320. The calling subscriber will now set up calls in the same manner as previously described but it will be noted that when either a subscriber in the north or south zones are dialled the ground placed in the bank accessible to wiper 364 of the rotary control switch RCS will appear at different positions on account of being switched by relay 384. Therefore, a call to north zone instead of causing the class minor switch CMS to stop in the second position will cause it to stop in the third position and a call to the south instead of causing the class minor switch to stop in the fourth position will cause it to stop in the fifth position. When the called subscriber answers, the same action will take place as previously described for a single subscriber having class B service. It will be noted, however, that the meter relay 30 will not operate except when ground pulses appear on either leads 35 or 37, and consequently when ground is connected to the meter pulse leads the meter connected thereto will operate. As will be noted the single and party line subscribers have identical line circuits and each line has a meter relay. The meter leads extending to this relay will be connected to two meters one of which will register calls made by the first party and the second of which will register calls made by the second party. This two party metering is given without the use of any special line equipment at the exchange and any of these equipments can, therefore, be used for either single or two party line service indiscriminately. It is therefore apparent with this type of arrangement that both single and party line subscribers may be in the same group when the jack per-station system of wiring is used.

In the case of special service calls to special operators which, of course, should not be metered against the subscriber, the classification switch, in conjunction with the first selector-repeater is so arranged that metering will be prevented and the special service operator obtains a direct line to the subscriber with the first selector-repeater bridge removed. This service is particularly re-

quired in conjunction with the present method of handling toll calls on the so-called CLR, or combined-line-and-recording basis, as well as pay station services. On these types of calls the subscribers dial the special service code upon the selector-repeater and classification switch which in turn causes the class minor switch CMS to move to its sixth position. When the class minor switch reaches 10 is sixth position the bridges at the selector-repeater are removed in a manner to be more fully described hereinafter.

In the case of reverting calls on a party line, the code dialled is arranged to produce 15 the same setting on the class minor switch CMS in order to remove the selector-repeater bridge and to connect the calling line direct to the reverting call switches.

In the case of calls for the operator it is 20 customary to dial only one digit, that is digit "0". This, of course, will not cause the classification switch to step into the bank nor will it cause the control switch to go into third position, because there is no second digit dialled 25 in. This condition, however, is met by arranging normal post springs on the classification switch which operates on the tenth level and produces the same conditions as those produced by dialling two or three digits 30 of the special service code.

Having briefly described the apparatus and its functions a detailed description will now be given.

25 *Line S² initiates a call*

Assume now that line S² initiates a call, a circuit may be traced for energizing line relay 7' by way of ground through the upper winding of relay 7', armature 14', upper line 49 conductor 5', through the substation circuit to lower conductor 6', armature 16', and through the lower winding of relay 7', to battery. Line relay 7', upon energizing, at armature 11' connects the cut-off relay 8' to 54 the test contacts in the line finder banks to apply negative battery potential to this contact to enable the line finder to cut through on the calling line and at 12' connects ground to the finder start lead 17' to initiate the operation of the line finder in a manner described in the aforementioned Saunders application or in a manner somewhat similar to Patent 1,688,588, issued to Lomax et al., on October 23, 1928. The line finder is operated 59 step-by-step in its vertical movement to find the group in which the calling line terminates and is then rotated step-by-step to find the calling line. When the test wiper 23 of the line finder encounters the negative battery potential applied through both resistance 13', and cut-off relay 8' by way of armature springs 11', the line finder will switch through and connect the subscriber's line conductors 5' and 6' to the line conductors 25 65 and 27 extending to the selector-repeater

shown in Fig. 2. The cut-off relay 8' is energized from ground in the line finder by way of test wiper 23, armature 11' and through the winding of cut-off relay 8', to battery. At armature 15' cut-off relay 8' 70 completes a locking circuit for itself and also connects ground to conductor 9' extending to the connector banks to guard this line against seizure from the connector and at armatures 14' and 16' disconnects the line relay 7' from the subscriber's line conductors. Line relay 7' deenergizes and at armature 11' opens the original energizing circuit at the cut-off relay 8' and at armature 12' opens the finder start lead. As soon as the subscriber's loop 75 is extended to the selector-repeater, line relay 202 is energized over the following circuit: from ground by way of normally closed springs controlled by armature 275, normally closed springs controlled by vertical off-normal springs 226, through the lower winding of differential relay 203, the lower winding of relay 202, normally closed springs controlled by armature 220, normally closed springs controlled by armature 245, conductor 27, through the finder and subscriber's loop back to conductor 25, normally closed springs controlled by armature 243, normally closed springs controlled by armature 219, through the upper winding of line relay 202, and 80 through the upper winding of differential relay 203 to battery. Differential 203 does not energize over the above traced circuit because its upper and lower windings are in opposition. Line relay 202, upon energizing, at 85 armature 223 and its working contact energizes the repeating relay 205 over an obvious circuit. The energization of repeating relay 205 is without effect at this time. At armature 224 line relay 202 closes a circuit for 90 slow-to-release relay 204 by way of grounded armature 244, armature 224 and its working contact and through the winding of release relay 204, to battery. Release relay 204, upon energizing, at armature 227 grounds the release trunk conductor 26 by way of normally closed springs controlled by armature 254; at armature 228 prepares the impulsing circuit to the classification switch CS; at armatures 229 and 231 prepares circuits for operating the finder switching relay 215 or the finder magnet 312 of the classification switch finder CSF dependent upon whether the wipers of the finder are standing in engagement with an idle classification switch; and at armature 232 opens a point in the release circuit and prepares the impulsing circuit to the vertical magnet of the selector repeater. 100

Assuming now that the wipers of the classification switch finder CSF are in engagement with a busy classification switch, guard wiper 316 will be in engagement with a contact having ground potential thereon with the result that this ground potential extending by way of conductor 310, armature 272 105

and its resting contact, armature 229, armature 239, to the lower terminal of finder switching relay 215 will short-circuit this relay from ground extending from grounded armature 231 and armature 240. Switching relay 215, therefore, does not energize and the ground extending to the lower terminal of switching relay 215 may be traced by way of vertical-off-normal springs 274, conductor 307, interrupter springs 313, and through the winding of the stepping magnet 312 to battery to energize the stepping magnet to rotate the wipers of the finder to search for an idle classification switch. At interrupter springs 313 stepping magnet 312 intermittently interrupts its own circuit and steps the wipers in search of an idle classification switch as long as the guard wiper 316 encounters ground potential on successive bank contacts of busy classification switches. When an idle classification switch is found guard wiper 316 no longer encounters a ground potential with the result that switching relay 215 is energized over the following circuit: from ground by way of armature 231, armature 240, winding of switching relay 315, vertical off-normal springs 274, conductor 307, interrupter springs 313, and through the winding of stepping magnet 312 to battery. Switching relay 215 energizes over the above traced circuit, but due to the high resistance of the switching relay 215 the stepping magnet 312 is not energized. At armature 269 switching relay 215 removes one of the shunting grounds from around the selector-repeater switching relay 206; at armature 270 prepares an impulsing circuit to the classification switch CS; at armature 271 closes a circuit for relays 383 and 384; at armature 272 connects ground to the guard lead 310 to prevent any other selector-repeater from seizing the selected classification switch; at armature 273 closes a locking circuit for itself independent of the vertical off-normal springs 274 which open on the first vertical step of the selector-repeater; at armature 276 prepares an impulsing circuit to the rotary magnet 284 of the class minor switch CMS; and at armature 275 connects grounded dial tone in place of ground through the lower windings of relays 203 and 202 and thence over the subscriber's loop for transmitting the dial tone to the calling subscriber in the well known manner. Responsive to the energization of the finder switching relay 215, relay 383 is energized over the following circuit: ground by way of armature 231, resistance 230, armature 271, conductor 309, wiper 315, conductor 319, armature 372, winding of relay 383, and through the lower winding of relay 384 to battery. Only relay 383 energizes over the above traced circuit since the relay 384 is marginal and will not energize in series with the resistance 230. At armature 374 relay 383

opens one point in the release circuit of the classification switch and at its working contact connects ground to the guard conductor 320 with which the guard wiper 316 is now in engagement. At armature 375 relay 383 prepares a locking circuit for two-step relay 381 at its working contact and at its resting contact opens the releasing circuit of the rotary control switch RCS.

When subscriber S2 hears the well known dial tone the subscriber will dial the first digit of the desired number. Responsive thereto when the calling device or dial is moved in an off-normal position the shunt springs SS2 are operated to shunt the receiver and transmitter and when the dial is released the impulse springs IS2 opens the circuit extending to the line relay 202 to de-energize the line relay a number of times dependent upon the digit dialled. Responsive to each deenergization of line relay 202 a ground impulse is transmitted by way of armature 223 and its resting contact, armature 228, armature 270, to impulse conductor 308. Each deenergization of the line relay 202 also transmits an impulse of current from ground by way of armature 244, armature 224 and its resting contact, armature 232 and its working contact, through the winding of series relay 208 to battery, and through armature 242 and the winding of vertical magnet 216 to battery for energizing series relay 208 and vertical magnet 216. Release relay 204 being a slow-to-release relay is maintained energized during the impulsing period even though its circuit is temporarily interrupted at armature 224. Series relay 208 is also a slow-to-release relay and therefore maintains its armatures in operated position during impulsing and at armature 246 closes a short-circuit around the upper windings of relays 210 and 211, and at armature 247 and its working contact closes another shunt circuit around the switching relay 206. This shunt circuit is placed around the switching relay 206 to prevent its energization when the vertical off-normal springs 249 are closed on the first vertical step of the selector-repeater. By the operation of the vertical magnet 216 the wipers of the selector-repeater are stepped in a vertical direction responsive to each impulse received by the vertical magnet. On the first vertical step the vertical off-normal springs of the selector-repeater are operated to close the following circuits: at vertical off-normal springs 226 direct ground is connected by way of the normally closed springs controlled by cam springs 221 to replace the grounded dial tone; vertical off-normal springs 233 prepares the circuit for the release magnet 217 of the selector-repeater; at vertical off-normal springs 249 closes a circuit for energizing the stepping relay 209; and at vertical off-normal springs 274 opens the original energizing cir-

cuit of finder switching relay 215. Relay 215 by this time is maintained energized over leads 310 and 307. The circuit for energizing the stepping magnet 209 may be traced as follows: from ground by way of armature 227, normally closed springs controlled by armature 238, armature 247 and its working contact, off-normal springs 249 and through the winding of stepping magnet 209 to battery. At armature 248 stepping relay 209 completes a locking circuit for itself extending by way of interrupter springs 235 of the rotary magnet 218. At armature 248 stepping relay 209 places an obvious ground shunt circuit around switching relay 206; and at armature 250 prepares a circuit for energizing the rotary magnet 218. When series relay 208 deenergizes shortly after the first series of impulses, a circuit may be traced for operating the rotary magnet 218 as follows: from ground by way of armature 227, normally closed springs controlled by armature 238, armature 247 and its resting contact, armature 250 and through the winding of rotary magnet 218 to battery. Responsive to the energization of the rotary magnet 218 the wipers of the selector repeater are rotated into engagement with the first set of bank contacts of the selected level and at interrupter springs 235 rotary magnet 218 opens the locking circuit of stepping relay 209 which deenergizes. At armature 250 the deenergization of the stepping relay 209 opens the circuit of the rotary magnet. The operation from now on is dependent upon whether the test wiper 278 encounters a grounded potential of a busy second selector or not. Assuming now that the second selector terminating in this first set of contacts is busy the test wiper 278 will encounter a ground potential which will maintain the switching relay 206 shunted to prevent its energization. This busy ground potential closes a circuit for energizing the stepping relay 209 by way of test wiper 278, armature 238 and its resting contact, interrupter springs 235, off-normal springs 249, and through the winding of stepping relay 209, to battery. Stepping magnet 209 again energizes and again completes the locking circuit for itself as well as to again complete the circuit for energizing the rotary magnet 218, to cause the wipers of the selector-repeater to rotate to the next set of contacts. The operation just described continues until the test wiper 278 no longer encounters a busy ground potential or until the wipers are rotated beyond the last set of contacts, whereupon the cam springs 221 are operated and the calling subscriber is given the busy tone in the well known manner. In case the next test contact encountered by test wiper 278 does not have a ground potential thereof, switching relay 206 will not be short-circuited with the result that the switching relay will energize over the fol-

lowing circuit: from ground by way of armature 227, winding of switching relay 206, interrupter springs 235, off-normal springs 249, and through the winding of stepping relay 209 to battery. Switching relay 206 energizes over the above traced circuit but stepping relay 209 being marginal does not energize on account of the high resistance of switching relay 206. At armature 236 switching relay 206 closes a loop circuit extending by way of wiper 277, armature 243 and its resting contact, armature 236, through the upper windings of relays 211 and 210, lower winding of repeating relay 205, normally closed springs controlled by armature 222, armature 234, resting contact of armature 245 and said armature, to wiper 279. The line relay of the second selector is energized over the above traced circuit to prepare the second selector for operation in the well known manner. At armature 238 and its working contact switching relay 206 connects grounded armature 227 to test wiper 278 to prevent any other selector repeater from seizing the selected second selector; at armature 240 opens the original energizing circuit of finder switching relay 215; at armature 241 prepares a circuit for energizing the switching through relay 207; and at armature 242 opens the circuit extending to the vertical magnet 216. The circuit just traced through the upper windings of relays 210 and 211 causes the energization of the holding relay 210 which at armature 251 completes a circuit through the lower winding of electro-polarized relay 211 to prepare relay 211 for operation when the called subscriber answers and reverses battery through its upper winding. The circuit extending through the lower winding of repeating relay 205 just traced is in opposition to the upper winding to cause a quick or slow deenergization of this relay in accordance with the length of line or resistance extending to the second selector while repeating impulses. The selector repeater SR now remains in this position until the next series of impulses are transmitted by the calling subscriber for operating the second selector. Referring now to Fig. 3 and at a time when impulses were transmitted over conductor 308 by line relay 202, it will be seen that these impulses extend over wiper 314, conductor 318, series relay 356, vertical magnet 354 of the classification switch CS, conductor 395, wiper 363 of the rotary control switch RCS, and through resistance 366, to battery. Responsive to this series of impulses the series relay 356 is maintained energized throughout the series of impulses while the vertical magnet 354 is operated for each impulse to step the wiper 358 of the classification switch opposite a certain level of contacts in accordance with the number of impulses received. On the first vertical step of the classification switch the vertical off-normal springs 351 and

352 are closed, the springs 351 to connect ground to the guard conductor 320 and the springs 352 for preparing the release circuit for the release magnet 353 of the classification switch CS. Slow-to-release series relay 356, upon energization, at armature 357 closes a circuit for energizing the stepping magnet 368 of the rotary control switch RCS to prepare the operating pawl to advance the rotary control switch when the stepping magnet 368 is deenergized. Shortly after this series of impulses series, relay 356 at armature 357 opens the circuit of the stepping magnet 368 with the result that the magnet deenergizes and advances the wipers 363 to 365, inclusive, of the rotary control switch from their first to their second positions. Wiper 363 disconnects the vertical magnet 354 from the impulsive circuit and connects the rotary magnet 355 thereto. The calling subscriber now dials the second digit of the desired number and the line relay 202 of the selector repeater is again intermittently operated in accordance with the number of impulses in the digit. At armature 224 series relay 208 is again energized during the impulsive period to shunt out the upper windings of relays 210 and 211 at armature 246. At armature 223 line relay 202 transmits impulses to the repeating relay 205 and to impulse conductor 308. Upon each deenergization of line relay 202, impulse repeating relay 205 deenergizes and at armature 234 opens the loop circuit extending by way of ground through the lower winding of the line relay of the second selector, wiper 279, armature 245 and its resting contact, armature 234 now open, normally closed springs controlled by armature 222, lower winding of impulse repeating relay 205, armature 246, armature 236, resting contact of armature 243 and said armature, wiper 277, and through the upper winding of the line relay of the second selector to battery. Impulse repeating relay 205 at armature 234, therefore, interrupts the circuit extending to the second selector a number of times corresponding to the number of times the line relay 202 of the selector repeater is deenergized. This repeating circuit is taken through the lower winding of impulse repeating relay 205 to compensate for the differences in line resistances or length of the trunk lines extending to the various second selector accessible from this selector-repeater. The seized second selector is, therefore, operated in the well known manner to extend the connection. The impulses generated by armature 223 of line relay 202 to impulse conductor 308 are transmitted over the impulse wiper 314, conductor 318, series relay 356, rotary magnet 355, conductor 395, wiper 363 now in second position, and through the resistance 366 to battery. Series relay 356 at armature 357 again energizes the stepping magnet 368 to position the operating pawl to advance the wipers of the rotary control switch from their second to their third position, while the rotary magnet 355 of the classification switch CS operates the wiper 358 in a rotary movement to engage with a contact jumpered in accordance with the local zone metering arrangement. In this case it will be assumed that the wiper 358 has been operated vertically three steps and then rotated three steps to ground conductor 397 accessible to wiper 364 of the rotary control switch RCS. When relay 356 deenergizes after this series of impulses stepping magnet 368 operates the wipers of the rotary control switch RCS from their second to their third position. When wiper 363 reaches its third position a circuit may be traced from grounded interrupter IG by way of armature 369 and its resting contact, upper winding of two-step relay 381, conductor 396, wiper 363, and through resistance 366 to battery. Two-step relay 381 is energized in its first step to close only armature 371 to prepare a circuit for operating the relay in its second step. When ground is removed from armature 369 by the rotation of the interrupter IG, ground by way of armature 375 and its working contact, armature, 371, the lower and upper windings of two-step relay in series now cause the two-step relay 381 to operate its armatures 370 and 369. At armature 369 the interrupter IG is disconnected from the relay 381 at its resting contact and at its working contact prepares a circuit for intermittently operating relay 385. At armature 370 two-step relay 381 completes a locking circuit for itself extending by way of grounded armature 375, armature 371, lower and upper windings of relay 381, armature 370, and through resistance 366 to battery. Relay 385 is intermittently operated by the impulse interrupter IG and at armature 380 transmits impulses to the stepping magnet 368 of the rotary control switch to cause the rotary control switch to advance step-by-step until wiper 364 encounters a grounded contact. At armature 379 relay 385 also transmits impulses to the rotary magnet 284 of the class minor switch CMS as follows: ground by way of armature 379, conductor 321, wiper 317, conductor 311, armature 276, and through the winding of rotary magnet 284 to battery. The wipers of the class minor switch CMS and the wipers of the rotary control switch RCS are, therefore, operated in unison until wiper 364 encounters the ground potential connected thereto by the operation of the classification switch wiper 358. In this case since the call was to the local or main zone the rotary control switch and the class minor switch are advanced only one step because at this step wiper 364 closes the following circuit: ground by way of wiper 358, the thirty-third bank contact

in the classification switch bank, jumper extending to terminal switch 361, conductor 397, wiper 364, and through the winding of relay 382 to battery. Relay 382 energizes 5 and at armature 373 completes a locking circuit for itself extending by way of either off-normal springs 362 of the rotary control switch RCS or by way of off-normal springs 351 of classification switch CS. At armature 10 372 relay 382 opens the circuit extending through relays 383 and 384 with the result that relay 383 deenergizes. At armature 374 and its resting contact relay 383 completes an energizing circuit for release magnet 353 15 by way of vertical off-normal springs 352 to cause the classification switch CS to release its wiper 358 to normal position, and at armature 375 and its working contact opens the locking circuit of two-step relay 381 where- 20 upon the latter relay releases and at the resting contact of armature 375 closes a circuit for operating the stepping magnet 368 to cause the latter magnet to operate in a buzzer like manner to rotate the switch back to its 25 normal position. The circuit for operating the stepping magnet 368 may be traced as follows: ground by way of armature 375 and its resting contact, conductor 390, multiple contacts accessible to wiper 365 and said 30 wiper, interrupter springs 367, and winding of stepping magnet 368 to battery. When both the classification switch CS and the rotary control switch RCS have returned to their normal position the off-normal springs 351 and 362 will remove the guarding and locking ground from conductor 320 and relay 382 and the latter relay thereupon de-energizes. The classification switch CS and the rotary control switch RCS are now in 35 40 normal position and may be selected for subsequent calls.

Returning now the selector repeater SR, it will be remembered that it was assumed that the call was from a subscriber who pays 45 for all his calls on a metered basis and that the call just made was for another subscriber in the same zone and that the rotary magnet 284 receives only one impulse to step the wipers of the class minor switch CMS to 50 their first position because relay 385 advanced the rotary control switch only one additional step when wiper 364 encountered the ground potential determined by the setting of the classification switch wiper 358. The 55 class minor switch remains in this position while the subscriber dials the remainder of the connection which is completed in a well known manner.

When the called subscriber answers, the 60 connector reverses battery in the well known manner thereby reversing the current flow in the upper winding of relay 211. Due to this reversal, the upper winding now assists the lower winding and relay 211 energizes. At 65 armature 253 relay 211 closes an obvious cir-

cuit for energizing reversing relay 201 to reverse battery back to the calling subscriber for supervisory purposes and at armature 252 prepares for energizing relay 213.

Referring now to Fig. 3 the impulse distributor ID constantly rotates in the direction as indicated by the arrow to cause the cam 344 to successively operate springs 345 to 350, inclusive, to close their contacts. When springs 345 are closed by cam 344 conductor 337 is grounded to operate relay 322 and all other similar relays connected to common lead 337. At armature 329 and its working contact relay 322 grounds conductor 301 for the interval of time for which it is 70 operated. In a like manner relays 323 to 327, inclusive, are operated to ground conductors 302 to 306, inclusive. The impulse distributor ID rotates at a constant speed and therefore causes conductors 301 to 306, 85 inclusive, to be grounded in sequence at different predetermined time intervals.

From the above description it can be seen that only one relay, such as relays 322 to 327, inclusive, can be operated at the same time 90 and, therefore, only one of the conductors 301 to 306, inclusive, will be grounded at the same time. In case of a fault, however, if one of the conductors 301 to 306 is grounded a circuit may be traced from the grounded conductor 95 through the terminating armature and its back contact to relay 328 and battery. In a like manner in case two or more of the conductors 301 to 306 become short-circuited due to a fault the operation of one of the relays completes an energizing circuit for alarm relay 328 from ground by way of the working contacts of the operated relay, one of the conductors and back through the other conductor which in this case is shorted, to the 100 resting contact of an unoperated armature and through the upper winding of relay 328, to battery. At armature 335 relay 328 closes a locking circuit for its lower winding; and at armature 336 closes a circuit for operating 110 an alarm so that the attendant may clear the fault. It will also be noted that this fault effects only the group of selector-repeaters which is individual to the conductors 301 to 306 and does not, therefore, effect the 115 other groups in the exchange.

After the called subscriber has answered and when conductor 306 is grounded by the operation of relay 327 responsive to the operation of springs 350, a circuit may be traced 120 for relay 213 as follows: grounded conductor 306, resting contact of armature 265 and said armature, lower winding of relay 213, armature 252, armature 266, wiper 280, and through the resistance to battery. Relay 213 125 energizes over the above traced circuit and at armature 258 completes an obvious locking circuit for itself through its upper winding. At armature 257 relay 213 prepares a circuit for operating the booster battery meter- 130

ing relay 213; at armature 259 relay 213 prepares a circuit for energizing the rotary magnet 290 of the time switch TS and at armature 260 prepares a circuit for connecting the 5 warning time tone to the calling subscriber's line.

Within a predetermined time interval after ground has been removed from conductor 306 by the rotation of the impulse distributor 10 ID, cam 344 is operated to close springs 345 and operate relay 322 to ground conductor 301. It will be remembered that the class minor switch CMS in this call was rotated to its first position and, therefore, a circuit for 15 energizing the booster battery metering relay 212 may be traced from ground by way of conductor 301, wiper 281 in its first position, armature 263, armature 257, and through the winding of relay 212 to battery. At armature 20 256, relay 212 completes a circuit for energizing two-step relay 214 in its first step over the following circuit: ground by way of armature 231, armature 256, armature 261, lower winding of two-step relay 214, and 25 through resistance 291 to battery. Two-step relay 214 energizes and operates to close only its armature 262. At armature 254 booster battery meter relay 212 substitutes booster battery through resistance 255 for the ground 30 connected to armature 227 and connects this booster battery potential by way of release trunk conductor 26, through the line finder, to test wiper 23, test contact of the calling subscriber's line, armature 15', conductor 9', 35 and through the winding of marginal meter relay 32 to battery. Meter relay 32 will not energize when guarding ground is connected over conductor 9' but will energize as soon as meter relay 212 energizes to connect 40 booster battery potential thereto. At armatures 53 to 57, inclusive, meter relay 32 connects the meter leads 43 to 47, respectively, to the meter conductors connected to the meters terminating on the terminal strip 59. It 45 will be noted that grounded conductor 301 is also connected to conductor 43 and that, therefore, a circuit may be traced at this time for operating the local subscriber's meter 31 as follows: from grounded conductor 301, 50 conductor 43, armature 53, conductor 48, and through the winding of the local subscriber's meter 31 to battery. The meter 31 is, therefore, operated one step responsive to the grounding of conductor 301 since at this time 55 the class minor switch CMS is in its first position and the meter relays 32 and 212 are operated.

When ground is removed from conductor 301 subscriber's meter relay 32 and meter relay 212 deenergize and relay 212 at armature 256 removes the shunt circuit from around the upper winding of two-step relay 214, whereupon relay 214 operates in its second step due to the energization of its 60 upper winding in series with its lower wind-

ing. At armature 261 two-step relay 214 opens a point in its original energizing circuit; at armature 263 opens a point in the circuit of meter relay 212; at armature 264 opens the locking circuit of relay 213; at 70 armature 265 and its resting contact opens a point in the original energizing circuit of relay 213 and at its working contact connects the impulse interrupter IG to the lower winding of relay 213 which, however, at this 75 time is ineffective because armature 266 is now open and because the class minor switch has only been operated to its first position; at armature 267 closes a circuit to the rotary magnet 290 of the time switch TS; and at 80 armature 268 opens a point in the circuit to the release magnet 289 of the time switch TS. Relay 213 deenergizes and is unable to again energize because the class minor switch wiper is in position one and because armature 266 85 of relay 213 is operated. The calling subscriber's meter 31 is, therefore, operated only once for this type of call since the time switch TS is not operated.

After the termination of the conversation 90 and responsive to the calling subscriber replacing his receiver the circuit of line relay 202 is interrupted with the result that the line relay 202 deenergizes. Responsive to the deenergization of line relay 202 the circuit of release relay 204 is opened at armature 224 and the circuit of repeating relay 205 is opened at armature 223. Impulse repeating relay 205 at armature 234 opens the loop circuit extending back to the second selector to 95 cause the second selector and the remaining switches in the switch train to release in the well known manner. It will be understood, of course, that the finder switching relay 215 releases as soon as the classification switch 100 CS and the rotary control switch RCS return to normal position and, therefore, remove ground from the ground conductor 310. Shortly after relay 205 deenergizes, 105 the slow-to-release relay 204 deenergizes and at armature 232 closes a circuit for operating both the release magnet 217 of the selector-repeater and the release magnet 283 of the class minor switch CMS over an obvious circuit. At armature 227 release relay 110 204 disconnects ground from release trunk conductor 26 to permit the cut-off relay 8' in the subscriber's line circuit to deenergize and to render the calling line available for calls by way of the connector banks. In 115 addition armature 227 opens the circuit of switching relay 206 which relay returns to its normal position. At armature 231 release relay 204 opens the locking circuit of two-step relay 214 with the result that this 120 relay returns to its normal position to close the circuit to the release magnet 289 of the time switch TS. By the operation of the various release magnets, the selector repeater, the class minor switch CMS, and the classi- 125

ification switch CS are returned to their normal position and all of the relays in Fig. 2 are in normal position and the selector-repeater SR is again available for use on other calls.

At this time it should be pointed out that for the particular class of metered service under discussion there will be another meter connected to this subscriber's meter leads 49 and 51 for metering calls to the north and south zones. It will now be assumed that calling subscriber S2 dials a number in the north zone instead of the local zone. The line finder, the selector-repeater, and the classification finder operate in the same manner as previously described. In this case since the call is to the north zone the impulses transmitted to the classification switch CS move the wiper 358 to ground a bank contact jumpered to conductor 392. It will be noted that this ground will extend from conductor 392 by way of armature 378 of relay 384 to the fifth bank contact accessible to wiper 364. The reason for extending the zone cross connections to contacts of relay 384 will be more fully described in connection with party line metering. After the rotary control switch RCS steps to third position, two-step relay 381 operates and completes the circuit for pulsing relay 385 and the latter relay pulses both the class minor switch CMS and the rotary control switch RCS as previously described until wiper 364 encounters the cut-off ground connected to its bank by the wiper 358 of the classification switch. The rotary control switch RCS, therefore, stops in position five when wiper 364 encounters a ground potential extending by way of conductor 392, armature 378 and conductor 389. In this case the rotary magnet 284 of the class minor switch CMS have received two impulses by the operation of relay 385 and has, therefore, moved its wipers to their second positions in the same manner as previously described. The classification switch CS and the rotary control switch RCS are now released and are available for use in other calls.

When the called subscriber answers, a pulse on lead 306 will operate relay 213 and when lead 302 is grounded by the impulse distributor ID and relay 323, relay 212 is energized to connect booster battery to the release trunk 26 to operate the meter relay 32. At the same time that relay 212 is energized, conductor 44, which is connected to conductor 302, is also grounded with the result that the meter connected to conductor 49 is operated. When the impulse distributor ID rotates cam 344 beyond springs 346 relay 323 deenergizes to remove ground from conductor 302 and conductor 44. Relays 212 and 32 thereupon deenergize and relay 214 operates in its second step. The operation up to this point is similar to that previously described

but in this case, since wiper 280 of the class minor switch CMS is in its second position, a circuit may be traced through the lower winding of circuit 213 to the impulse interrupter IG as follows: from ground by way of impulse interrupter IG, working contact of armature 265 and said armature, lower winding of relay 213, armature 252, second bank contact, wiper 280, and through the resistance to battery. Impulse interrupter IG energizes relay 213 over the previously traced circuit every thirty seconds and since relay 214 is fully energized the locking circuit for relay 213 is not completed. Relay 213, therefore, transmits impulses by way of armature 259 and armature 267 to the rotary magnet 290 of the time switch TS. The time switch TS is, therefore, operated one step every thirty seconds. When wiper 285 of the time switch TS reaches its ninth position a warning tone will be connected by way of armature 260, wiper 285, and conductor 286 to the lower talking conductor to indicate to the calling subscriber that the five minute period is nearly up and that unless he hangs up within thirty seconds he will be metered for another period.

Assuming that the calling subscriber does not release the connection, another pulse will step the time minor switch TS to its tenth position. When wiper 287 of the time switch TS reaches its tenth position a shunting ground circuit is connected around relay 214 upon the deenergization of relay 213 as follows: ground by way of armature 259 and its resting contact, tenth contact and wiper 287, through the lower and upper windings of relay 214, armature 262, to ground at armature 231. Two-step relay 214 thereupon deenergizes and at armature 268 completes the circuit for the release magnet 289 of the time switch TS to release the time switch to its normal position. At this point the relays and apparatus are in identical positions to those existing at the beginning of the call when the called subscriber answered. Therefore, when conductor 306 is again grounded relay 213 is again operated and when conductor 302 is again grounded meter relay 212 connects booster battery to the release trunk conductor 26 to operate the meter relay 32 and complete the circuit for operating the subscriber's meter 28' a second step for this call. From this point on the time switch again starts operating as previously described to again operate the meter in case the subscriber maintains the connection.

In case the calling subscriber dials a number in the south zone the classification switch wiper 358 will be stepped to a point which in turn is jumpered to conductor 293 and after the rotary control switch RCS reaches its third position relay 385 impulses both the class minor switch CMS and the rotary control switch RCS until wiper 364 of the ro-

5 tary control switch encounters the cut-off ground connected to conductor 393. In this case the class minor switch is stepped to its fourth position when wiper 364 encounters the cut-off ground. When the called subscriber answers, the same action just described will take place as outlined for calls to the north zone with this exception, that the relay 32 and meter relay 212 are not operated except when 10 the ground pulse appears on lead 304 by way of the impulse distributor ID and meter impulse relays MIR. When ground is connected to lead 304 booster battery meter relay 212 connects booster battery to the release 15 trunk to operate meter relay 32 and since conductor 304 is connected to conductor 46 the operation of armature 56 of meter relay 32 connects this ground to the left-hand winding of meter 28' with the result that the meter 20 is operated one step to charge for this call. The operation of the time switch TS and the release of the connection will be the same as previously described.

25 From the above description it can readily be seen that the class of metered service as outlined under class B can easily be given by omitting the meter 31 connected to lead 48 and connecting a double wound meter to leads 49 and 51. In the case of service under 30 class C, the meter 31 on lead 48 is omitted and a meter is connected to either lead 49 or lead 51 as the case may be.

35 It is desirable to record the calls to the north zone separate from the south zone this can be easily done by connecting a single wound meter to lead 49 and another single wound meter to lead 51 in place of the double wound meter 28'.

40 As previously stated, metered party line service is furnished with this equipment but in this case the party line subscribers are given class B service, that is, he pays a monthly rate sufficient to insure free calls into the main or local zone and pays for calls 45 on the time basis to the north and south zones. In the case of calls from the first party on the party line, such as subscriber S, the operation of the equipment is identical to that described for single line subscribers having class B 50 service.

55 The second party's telephone on a telephone party line is equipped with a dial which delivers a ground pulse to the line prior to the sending of the impulses for each digit. Referring now to Fig. 4, springs 1, 2, 3 and 4 are the shunt spring assembly of a calling device somewhat similar to the shunt spring assembly shown in Fig. 3 of Patent 1,642,822, issued September 20, 1927, to H. F. 60 Obergfell. When the calling device is moved off-normal prior to sending the impulses, the cam 62 is rotated in the direction of the arrow and the insulated lug 61 which is secured to spring 3 slides in the rounded projection in 65 cam 62 and permits all of the springs 1, 2,

3 and 4 to simultaneously engage with each other for a short interval of time and after the cam 62 is rotated beyond the insulated lug 61 the springs 1, 2 and 3 are held in engagement with each other while the spring 4 is separated therefrom. A shunt spring assembly of this type is shown connected to the substation circuit of the party line subscriber S'. A ground impulse is therefore transmitted over line conductors 5 and 6 at the start and at the end of each digit transmitted by subscriber S'. The fact that ground impulses are sent out before and after each digit has no particular significance because only the first ground pulse is utilized to produce the desired effect.

70 It will now be assumed that subscriber S' initiates a call and responsive to the removal of the receiver the line relay 7 is energized over the subscriber's loop to perform the 75 same functions as described for relay 7' of the individual subscriber's line. The line finder is initiated responsive to the operation of relay 7 to find the calling line and switch the same through to the selector-repeater SR. The line relay 202 and the release relay 204 operate in the same manner as previously described. The classification finder CSF is also operated to find an idle 80 classification switch whereupon relay 215 is 85 energized to transmit dial tone to the calling subscriber as previously described.

90 The functions just described are identical with the operations described for a single line subscriber, but now when the subscriber S' operates his calling device to an off-normal position the shunt springs SS' are operated to ground conductors 5 and 6 whereupon the differential relay 203 in the selector-repeater 95 is unbalanced with the result that the differential relay is energized. Responsive to the energization of the differential relay 203 a circuit may now be traced for energizing relay 383 and marginal relay 384 as follows: 100 from ground by way of armature 225, armature 271, conductor 309, wiper 315, conductor 319, armature 372, winding of relay 383, and through the lower winding of marginal relay 384 to battery. Since resistance 230 is excluded in the above traced circuit the marginal relay 384 is energized and locks itself 105 energized over armatures 376 and 374. By the operation of relay 384 it will be seen that the north and south zone conductors 392 and 393 are transferred to different bank contacts 110 in the bank accessible to wiper 364 in order to operate the proper party line subscriber's meter, as will be more fully described hereinafter. The calling subscriber S' will now 115 set up the connection in the same manner as previously described. In case the subscriber calls another subscriber in the same or local zone the setting of the classification switch CS and the rotary control switch RCS are 120 the same as previously described to cause the 125 130

same setting of the class minor switch CMS. The booster battery meter relay 212 and the subscriber's meter relay 30 are operated in the same manner as previously described but 5 since no meter is connected to meter lead 33 the subscriber is not charged for calls into the local zone.

In case the subscriber S' dials a number in the north zone the setting of the classification switch CS is the same as previously described and now since relay 384 is in operated position the rotary control switch RCS rotates wiper 364 to its sixth position in engagement with conductor 388 instead of 10 389 before the cut-off ground is encountered by said wiper. The class minor switch CMS is, therefore, operated to its third position with wiper 281 in engagement with the bank contact terminating conductors 45 and 303. 15 When conductor 306 is grounded by the impulse distributor ID the relay 213 is energized to complete the relay operations previously set forth. When conductor 303 is grounded booster battery meter relay 212 20 energizes to connect booster battery to the release trunk conductor 26 to operate meter relay 30. At the same time meter relay 30 is operated ground extending by way of conductor 303 and conductor 45, armature 40, 25 and conductor 35 operates meter 29 individual to subscriber S'. The operation of the time switch and the release of the connection is the same as previously described for other calls to the north zone.

In case subscriber S' dialled a number in the south zone the classification switch CS would assume the setting assigned to the south zone to ground conductor 393. Since relay 384 is now energized, grounded conductor 393 now extends to the eighth contact accessible to wiper 364 of the rotary control switch RCS, with the result that wiper 281 of the class minor switch CMS is operated in engagement with conductor 47 40 when the wiper 364 of the rotary control switch RCS encounters the cut-off ground as determined by the setting of the classification switch. After the called subscriber answers and when conductor 306 is grounded relay 45 213 is again energized and when the impulse distributor grounds conductor 305 meter relay 212 will connect booster battery to the release trunk conductor 26 to again operate the meter relay 30. Since conductor 305 is 50 connected to conductor 47 the ground impulse connected to conductor 305 will now extend by way of conductor 47, armature 42, conductor 37 and through the left-hand winding of meter 29 to battery. Meter 29 is 55 thereupon energized to operate the meter to charge for this call. The operation of the time switch TS and the release of the connection is the same as previously described 60 for a single subscriber on calls to the north 65 zone.

It will now be assumed that a calling subscriber commences to dial before dial tone is received. As will be remembered the calling subscriber is not given the dial tone until the classification finder has found an idle 70 classification switch which determines the type of metering to be applied to the calling subscriber's line. The selector-repeater SR is, therefore, arranged to be operated vertically to the level dialled and then automatically rotated beyond the bank contact whereupon the calling subscriber is given a busy tone. In case this condition was not provided for, a classification switch may be seized after a number of impulses of the first 75 digit have been transmitted with the result that the classification switch CS would not be set in accordance with the complete digit dialled and, therefore, the metering would not be in accordance with the zone called. 80 Under these conditions and responsive to the first impulse the vertical magnet 216 is operated to step the wiper one vertical step and to operate the selector-repeater vertical off-normal springs. At vertical off-normal 85 springs 274 the original energizing circuit of the classification finder switching relay 215 is opened before this relay can energize and complete its locking circuit. Since finder 90 switching relay 215 did not energize, the selector-repeater switching relay 206 is maintained shunted over the following circuit: ground by way of armature 269, armature 237, through the winding of switching relay 206 and to ground at armature 227. Responsive to the remaining impulses in the first 95 digit the vertical magnet operates the wipers of the selector-repeater opposite the level dialled whereupon the rotary magnet is operated in the same manner as previously described to rotate the wipers in search of an idle second selector. However, since the selector-repeater switching relay 206 is shunted, the rotary magnet will continue to operate the wipers of the switch until the 100 wipers are rotated beyond the bank contact whereupon the cam springs 221 are operated to connect the busy tone to the calling subscriber over the following circuit: from busy 105 tone by way of cam springs 221, vertical off-normal springs 226, through the lower windings of differential relay 203 and line relay 202, normally closed springs controlled by armature 220, normally closed springs controlled by armature 245, through the lower 110 talking conductor 27 and over the calling subscriber's loop. When the calling subscriber hears the well known busy tone he will replace his receiver and release the finder and selector repeater and will again call, this time 115 waiting for dial tone.

In the case of special service calls to a special operator, which of course should not be metered against subscribers, the classification switch in conjunction with the selector 120 repeater and will again call, this time 125 waiting for dial tone.

repeater is so arranged that metering will be prevented and the special service operator obtains a direct line to the subscriber with the first selector-repeater bridge removed. This type of service is required in conjunction with the present methods of handling toll calls on the so-called CLR, or combined line and recording basis as well as for pay-station service. When making a call to a special service operator the calling subscriber removes his receiver and waits for dial tone. The line finder and the relays in the selector-repeater are operated in the same manner as previously described and when the calling subscriber receives dial tone he will dial the number assigned to special service calls. Responsive to the digits dialled in the special service call the wiper 358 of the classification switch CS is operated to ground conductor 398 terminating in the ninth bank contact accessible to wiper 364. Relay 385 therefore impulses the rotary control switch RCS and the class minor switch CMS until wiper 364 encounters this cut-off ground. The class minor switch CMS is, therefore, stopped in its sixth position with the result that the switch through relay 207 of the selector-repeater SR is operated from ground at armature 241 to battery connected to wiper 280. At armature 244 switching through relay 207 opens the circuit of the release relay 204 as well as opening a point in the release circuits of the selector-repeater and the class minor switch release magnets. At armatures 243 and 245 relay 207 disconnects the selector-repeater bridges and connects the conductors 25 and 27 direct through to the wipers 277 and 279, respectively. Holding ground is now fed back over test wiper 278 for maintaining the switching relay 206 in energized position after the release relay 204 deenergizes and disconnects ground at armature 227 from the upper terminal of switching relay 206. The calling subscriber's line is now extended direct to the operator's position and the call from hereon is extended by the operator in the well known manner. After termination of the conversation, the holding ground is removed from switching relay 206 with the result that this relay and switching through relay 207 deenergize. By the deenergization of relay 207 armature 244 completes the circuits to the release magnets 217 and 283 to release the selector repeater and the class minor switch to their normal positions.

In the case of reverting calls on party lines, the code digits dialled are arranged to operate the classification switch CS and the class minor switch CMS so that the class minor switch CMS will be stopped in sixth position to operate the switching through relay 207 which relay energizes and connects the calling subscriber's loop direct to the reverting call switches by way of wipers 277 and 279 in order to complete the reverting

calls. In reverting calls the wiper 358 of the classification switch CS is therefore operated to a position to ground the ninth bank contact accessible to wiper 364 in order to set the class minor switch CMS in its sixth position. 70

In case of calls for the operator, it is customary to dial only one digit, that is, the digit "O". This of course will not cause wiper 358 of the classification switch CS to step into the bank nor will it cause the control switch to go into third position because there is no second digit dialled. This condition is met by providing normal post springs which are operated when the classification switch wiper 358 is operated opposite the "O" level of the classification switch bank. When wiper 358 is operated opposite the "O" level the normal post springs 359 operate to ground conductor 398 or the ninth position bank contact accessible to wiper 364 and at springs 360 connects ground to conductor 399 to energize the stepping magnet 368 to advance the wipers of the rotary control switch RCS when the magnet opens its interrupter springs 367 and deenergizes as a result thereof. When rotary control switch RCS reaches its third position two-step relay 381 is energized to complete the circuit for pulsing relay 385 and pulsing relay 385 operates both the rotary control switch and the class minor switch in the same manner as previously described. In this case the class minor switch is stopped in its sixth position to energize the switching through relay 207 to connect the subscriber's line direct to the operator's position. It will be seen, therefore, that with the aid of the normal post springs NPS on the classification switch the same conditions are produced as those produced by dialling a special service digit code. 105

It will be noted that from the foregoing description that the metering scheme outlined herein does not only cover means for giving booster battery metering over the release trunk in conjunction with line finders but covers several metering features which are believed to be novel in view of the known zone and metering arrangement. As a matter of fact while zone and time metering are well known, it is believed that the introduction of a method whereby a subscriber can be given the choice of several classes of metered service is new. In addition, this method makes it possible to furnish two party metering service without any special line equipment at the exchange. 110

Another feature which is obtained by the use of the classification switch is the ease with which circuit conditions can be produced in the selector-repeater which will permit giving a combined line and recording and paystation service without the use of complicated intermediate repeater equipment. In addition it can be readily seen that 115 120 125 130

the jumpering arrangement between the banks of the classification switch and the rotary control switch can be easily and readily changed to produce any desired setting of the class minor switch CMS associated with the selector repeater. It will also be noted that in so far as metering is concerned it is immaterial whether party lines and individual lines are in the same group and that it is not necessary to provide separate groups of lines for the different classes of metered service.

Having described the invention what is considered new and is desired to have protected by Letters Patent will be set forth in the following claims:

What is claimed is:

1. In a measured service telephone system wherein a group of subscribers' lines receive different classes of metered service, means for charging some of said lines for every completed connection, means for giving other of said lines free service to local zones and for charging for every completed call to other zones, means for giving the remaining lines in said group free service to the local and a near zone and for charging for every completed call to other zones, and means common to said group of lines for controlling the charging means.

2. In a measured service telephone system wherein a group of subscribers' lines receive different classes of metered service, a different number of meters individual to each line dependent upon the class of metered service each line receives, and means for operating a particular one of the meters individual to a calling line in response to the called party answering on a completed call to a called line, the particular meter operated being dependent upon the location of the called line and the class of metered service said calling line receives.

3. In a measured service telephone system wherein a single group of subscribers' lines receive different classes of metered service, there being both individual and party lines in said group, a different number of meters individual to each subscriber dependent upon the class of metered service each line receives, and means for operating a particular one of the meters individual to a calling subscriber dependent upon the location of the called line and the class of metered service said calling line receives.

4. In a measured service telephone system wherein a group of subscribers' lines receive different classes of metered service, a meter relay for each line, means for operating the meter relay of the calling line after a connection has been extended to a called line and the called party has answered, a different number of meters for each line, the number of meters for each line being dependent upon the class of metered service each line

receives, all the meters individual to the calling line being prepared for operation responsive to the operation of said meter relay, and means for operating only a particular one of the meters of the calling line.

5. In a telephone system wherein a group of subscribers' lines receive different classes of metered service, a plurality of meter conductors common to said group of lines, a corresponding plurality of meter leads individual to each line, a meter relay individual to each line, a different number of meters for each line and only certain ones of said individual meter leads connected to meters in accordance with the class of metered service each line receives, means for extending a connection from a calling line in said group to a called line and for selecting a particular one of said common meter conductors in accordance with the location of the called line, and means for operating the meter relay of the calling line to connect corresponding meter leads to corresponding meter conductors after the called party answers to operate only the calling subscriber's meter over the selected common conductor and corresponding meter lead in case a meter is connected to this individual lead.

6. In a measured service telephone system, a group of subscribers' lines, a meter relay for each line, a plurality of meter conductors common to said group and connected to each meter relay, a different number of meters for each line dependent upon the class of metered service each line receives, means for extending a connection from a calling line in said group to a called line and for selecting a particular one of said conductors in accordance with the location of the called line, means controlled over said selected conductor for operating the meter relay of the calling line over said connection after the called party answers, means responsive to the operation of said relay for connecting said common meter conductors to the meters of the calling line, and means for operating only the meter connected to said selected conductor.

7. In a measured service telephone system, a group of subscribers' lines, a meter relay for each line, a variable number of meters for each line dependent upon the class of metered service each line receives, a plurality of individual meter leads for each line connected to its individual meter relay, each individual meter lead connected to a meter or not dependent upon the class of metered service each subscriber receives, a plurality of meter conductors common to said group and connected to each meter relay, means for extending a connection from a calling line in said group to a called line and for selecting a particular one of said common meter conductors in accordance with the location of the called line, means controlled over the selected

- conductor for operating the meter relay of the calling line over said connection after the called subscriber answers, means controlled by the operation of said meter relay for connecting each said individual meter lead to a corresponding one of said common meter conductors, and a circuit including said selected common conductor and its corresponding individual lead completed responsive to the operation of said relay for operating one of the subscriber's meters in case a meter is connected to such individual meter lead. 8. In a measured service telephone system, a calling subscriber's line, a plurality of meters for said line, a plurality of meter conductors common to said line and other subscribers' lines, a meter relay for said line having contacts for connecting each of said conductors to a meter of the calling line when operated, means for selecting a particular one of said conductors responsive to the extension of a connection from the calling line to a called line, means controlled over the selected conductor for operating said meter relay when the called party answers, and a circuit completed over said selected conductor for operating only one of said meters responsive to the operation of said meter relay. 9. In a measured service telephone system, a group of subscribers' lines, meters for said lines, a plurality of meter conductors common to said lines, means individual to each of said lines for connecting said meters to said conductors, means for selecting a particular one of said conductors responsive to the extension of a connection from a calling one of said lines to a called line, means for transmitting impulses to successive ones of said conductors at predetermined intervals, and means responsive to the called party answering for rendering the impulses transmitted to said selected conductor effective to operate the individual connecting means of the calling line and the calling subscriber's meter. 10. In a measured service telephone system, a group of subscribers' lines, means for establishing a connection between a calling one and a called one of said lines, meter conductors common to said lines, a plurality of subscribers' meters adapted to be connected to said conductors, means individual to each of said lines for connecting said meters to said conductors, and means common to said lines for operating the individual connecting means of a calling one of said lines responsive to the called party answering to operate only the calling subscriber's meter over one of said conductors. 11. In a measured service telephone system, a calling line, a plurality of meters for said line, means for extending connections to called parties in local and distant zones, means for selecting a particular one of said meters in case the called party is in the local zone or a different one of said meters in case the called party is in the distant zone to determine the charge to be assessed against the calling subscriber, and means operated by the response of the called parties for operating the selected meter to assess said charges. 12. In a measured service telephone system, a calling line, a plurality of meters for said line, means for extending connections to called parties in local and distant zones, means for selecting a particular one of said meters in accordance with the location of the called parties to determine the charge to be assessed against the calling subscriber, means operated by the response of the called parties for operating the selected meter to assess said charges, a time switch associated with said selecting means, and means for operating said time switch only on calls to distant zones to reoperate the selected meter at predetermined time intervals as long as the connection is maintained. 13. In a measured service telephone system, a calling line, a plurality of meters for said line, a plurality of automatic switches accessible to said line and used in setting up connections to called parties in local and distant zones, means on the calling line for transmitting a plurality of series of impulses to operate said switches to extend a connection from the calling line to a called line, means responsive to the first and second series of impulses for selecting a particular one of said meters in accordance with the location of the called line to determine the charge to be assessed against the calling subscriber, and means operated by the response of the called party for operating the selected meter to assess said charge. 14. In a measured service telephone system, a calling line, a plurality of meters for said line, a plurality of automatic switches accessible to said line and used in setting up connections to called parties in local and distant exchanges, zone metering equipment associated with the first numerical switches in said plurality of switches, means responsive to the initiation of a call by the calling line for seizing one of said first numerical switches, means on the calling line for transmitting a plurality of series of impulses to operate some of said automatic switches to extend the connection to a called line, means responsive to the first and second series of impulses for setting said zone metering equipment to select one of said plurality of meters to determine the charge to be assessed against the calling subscriber, and means operated by the response of the called party for operating the selected meter to assess said charge. 15. In a measured service telephone system, a calling line, a plurality of meters for

- said line, a plurality of automatic switches accessible to said line and used in setting up connections to called parties in local and distant exchanges, zone metering equipment associated with the first numerical switch in said plurality of switches, a zone classification switch temporarily associated with the first numerical switch when said first numerical switch is seized responsive to the initiation 5 of a call on said calling line, means on the calling line for transmitting a plurality of series of impulses to said automatic switches to extend the connection to a called line, means responsive to the transmission of the 10 first and second series of impulses for operating said zone classification switch to determine the charge to be assessed against said calling subscriber, means responsive to the operation of said zone classification switch 15 for setting said zone metering equipment to select one of said meters in accordance with the determined charge, and means operated by the response of the called party for operating the selected meter to assess said charge. 20
16. In a measured service telephone system, a group of subscribers' lines each having individual metering equipment, a group of automatic switches for use by this group of lines for extending connections to called subscribers' lines, a group of meter conductors common to all said switches in the group and all said conductors normally connected to each individual metering equipment, means common to the said group of lines and 25 switches and other similar groups of lines and switches for determining the metering operation to take place on completed connections to called lines, and means for controlling the operation of each individual metering equipment over said common conductors as determined by said common means after called subscribers answer in completed connections. 30
17. In a telephone system, a group of lines, a meter and a meter relay for each of said lines, a group of trunk lines, a group of conductors common to said trunk lines and each conductor extending therefrom to each of said meter relays, means responsive to a call on one of said lines for taking one of said trunk lines into use to extend a connection toward a called line and for preparing a particular one of said common conductors for use dependent upon the location of the called line, means in said trunk line controlled over said particular conductor for operating the calling line's meter relay after the called subscriber answers, and means for operating the calling subscriber's meter over said particular conductor responsive to the operation of said meter relay to charge for the call. 35
18. In a telephone system, a group of lines, a meter and a meter relay for each of said lines, a group of trunk lines, a group of conductors common to said trunk lines and each conductor extending therefrom to each of said meter relays, means responsive to a call on one of said lines for taking one of said trunk lines into use to extend a connection toward a called line and for preparing a particular one of said common conductors for use dependent upon the location of the called line, and means for operating the calling subscriber's meter over said particular conductor responsive to the operation of said meter relay to charge for the call. 40
19. In a measured service telephone system, a calling line, a meter relay and a meter therefor, a group of trunk lines, meter conductors common to said trunk lines and each conductor connected to said meter relay, means for extending a connection over one of said trunk lines and for selecting one of said conductors, means controlled over said selected conductor for operating the meter relay over said trunk line connection, and means responsive thereto for operating the meter over said selected conductor. 45
20. In a measured service telephone system, a group of subscribers' lines, individual metering equipment for each of said lines, a group of trunk lines, a meter switch associated with each of said trunk lines, a group of relays common to said group of trunk lines, a group of conductors common to said group of trunk lines and said group of subscribers' lines, said conductors extending from the banks of each of said meter switches to each individual metering equipment and to said group of relays, means for operating said relays to successively transmit ground-ed impulses to each of said conductors at pre-determined timed intervals, means responsive to a call on one of said subscriber's lines for taking one of said trunk lines into use and for operating the meter switch associated therewith to select one of said common conductors in accordance with the zone in which the called line is located, and means in said trunk line responsive to the called party answering for rendering the impulses transmitted by said relays effective to operate the calling subscriber's metering equipment over the selected one of said common conductors. 50
21. In a telephone system, a group of calling lines, individual metering equipment for each of said lines, a group of trunk lines, a group of conductors common to said trunk lines and extending therefrom to each individual metering equipment, means responsive to a call on one of said subscriber's lines for taking one of said trunk lines into use to extend a connection toward a called line and for preparing a particular one of said common conductors for use dependent upon the zone in which the called line is located, and means responsive to the called party answering for operating the calling subscriber's 55

- metering equipment jointly over said trunk line and over said prepared conductor to charge the calling subscriber for the call.
22. In a measured service telephone system, three subscriber's lines each having a different class of metered service, a different number of meters individual to each line dependent upon the class of service each line receives, a plurality of meter conductors, each of said conductors common to said lines, means for grounding said conductors in sequence at predetermined time intervals, means for selecting one of said conductors, means individual to each line for connecting said meters to different ones of said conductors, and means for rendering only the ground impulses to said selected conductor effective to operate the calling subscriber's individual connecting means and a particular calling subscriber's meter. 70
23. In a measured service telephone system, a group of subscribers' lines having a first and a second party on each line, means for establishing a connection between a calling first party on one of said lines and a called line, a meter for each party on each of said lines, a meter relay for each of said lines, means common to said lines for selecting all the meters individual to each first party in the group in response to the setting up of said connection, and means for operating the meter relay associated with the calling line to operate only the said calling party's individual meter when the called party answers. 80
24. In a measured service telephone system, a group of subscribers' lines having a first and a second party on each subscribers' lines, a meter for each party on each of said lines, a meter relay for each of said lines, means for establishing a connection between a calling first party on one of said lines and a called line, means common to said lines for selecting all the meters individual to each first party in the group in response to the setting up of said connection to a called line, means for operating the meter relay associated with the calling line to operate only the said calling party's individual meter when the called party answers, and means for repeating the operation of said meter relay and meter in case the connection is held for a predetermined length of time. 90
25. In a measured service telephone system, a group of subscribers' lines having a first and a second party on each line, a plurality of meters individual to each party on said lines, trunk lines for use by this group of subscribers' lines for extending connections to called subscribers' lines, means in said trunk lines for determining which party on a calling line is calling, means common to said subscribers' lines for selecting all the meters individual to all the first parties in the group in accordance with said determining means and for further selecting a particu- 100
- lar one of said selected meters in accordance with the established connection to a called line, and means for operating the particular selected meter when the called party answers. 105
26. In a measured service telephone system, a group of subscribers' lines including both individual and party lines, meters for the subscribers, a meter relay for each line, a group of common meter conductors connected to each meter relay, a plurality of said conductors for use in operating individual line meter and the first party meters on party lines, others of said conductors for use in operating the second party meters on party lines, means for connecting a calling line with a called line, means for selecting one of said plurality of conductors in accordance with the location of the called line in case an individual line or a first party on a party line is calling and for selecting one of said other conductors in accordance with the location of the called line in case a second party on a party line is calling, and means for operating the meter relay of the calling line when the called party answers to connect and operate the calling subscriber's meter over the selected conductor. 115
27. In a measured service telephone system, a group of subscribers' lines including both individual and party lines, meters for the subscribers, a meter relay for each line, a group of common meter conductors connected to each meter relay, a plurality of said conductors for use in operating individual line meters and the first party meters on party lines, others of said conductors for use in operating the second party meters on party lines, means for connecting a calling line with a called line, means for selecting one of said plurality of conductors in accordance with the location of the called line in case an individual line or a first party on a party line is calling and for selecting one of said other conductors in accordance with the location of the called line in case a second party on a party line is calling, means for transmitting ground impulses to successive ones of said conductors at predetermined intervals, said impulses normally ineffective, and means responsive to the called party answering for rendering the impulses transmitted to said selected conductor effective to operate both the meter relay of the calling line and the calling subscriber's meter. 120
28. In a measured service telephone system, a group of subscribers' lines, meters for said lines, a meter relay for each line, a plurality of common meter conductors connected to each meter relay, means for successively connecting ground impulses to successive ones of said conductors at predetermined intervals, means for connecting a calling line with a called line, means for selecting one of said conductors in accordance with the location of a called line re- 125
- 130

sponsive to one of said lines of said group extending a connection thereto, means responsive to the called party answering for rendering the impulses transmitted to said selected conductor effective for operating both the meter relay of the calling line and the calling subscriber's meter, and means operative in case more than one of said conductors are simultaneously grounded for operating

10 an alarm.

29. In a measured service telephone system, a group of subscribers' lines including both individual and party lines, individual meters for the parties on said lines, a group 15 of common meter conductors, a plurality of said conductors for use in operating the meters on individual lines and the first party meters on party lines, other of said conductors for use in operating the other party meters on party lines, means for connecting calling lines with called lines, means for selecting one of said plurality of conductors in accordance with the location of a called line in case an individual line or a first party on a party 20 line is calling and for selecting one of said other conductors in accordance with the location of the called line in case one of said other parties on a party line is calling, and means for operating the calling party's individual meter over the selected conductor 25 when the called party answers.

30. In a measured service system, a calling subscriber's line, a local zone meter, a first zone meter, and a second zone meter individual to said line, called lines located in the local, first, and second zones, means for establishing connections between said line and said called lines, means for selecting the local zone meter in case the calling line establishes 35 a connection to a called line in the local zone, for selecting the first zone meter in case the calling line establishes a connection to a called line in the first zone, and for selecting the second zone meter in case the calling line establishes 40 a connection to a called line in the second zone, and means for operating the selected meter responsive to the called party answering.

In witness whereof I hereunto subscribe my
50 name this 15th day of August, A. D. 1930.
JOHN E. OSTLINE.
